Inventor:

UNITED STATES PATENT OFFICE.

DUNCAN W. BOYD, OF CHICAGO, ILLINOIS.

FIREPROOF FLOORING.

SPECIFICATION forming part of Letters Patent No. 775,516, dated November 22, 1904.

Application filed February 20, 1904. Serial No. 194,468. (No model.)

To all whom it may concern:

Be it known that I, DUNCAN W. BOYD, a citizen of the United States of America, residing at Chicago, in the county of Cook and State 5 of Illinois, have invented certain new and useful Improvements in Fireproof Flooring, of which the following is a specification.

My invention relates to certain new and useful improvements in fireproof flooring; and 10 its object is to produce a device of this class which shall have certain advantages, which will appear more fully and at large in the course of this specification.

To this end my invention consists in certain 15 novel features of construction, which are clearly illustrated in the accompanying drawings and described in this specification.

In the aforesaid drawings, Figure 1 is a sectional perspective through my improved floor, 20 the line of the section being indicated by the line 1 1 in Fig. 2; and Fig. 2 is a sectional perspective of the same floor, the line of the section being indicated by the line 2 2 in Fig. 1.

In the drawings, A A indicate the steel 25 beams upon which the floor is built. A false floor is ordinarily built below the level of the steel beams to give a surface upon which the floor material may be laid. A series of tiles B C are then laid upon this false floor, the 30 same being laid in alternate parallel rows. Each tile B, it will be seen, is hollow and provided with suitable transverse partitions to give it the necessary strength, and each has rectangular upper and lower surfaces and is 35 trapezoidal in cross-section. The tiles B are laid with their larger end at the top, as indicated. The tiles C are of much less height than the tiles B, but, like the tiles B, are trapezoidal in cross-section, these tiles, how- 40 ever, being laid with their smaller surfaces at the top. Each tile C has in the preferred form of construction a suitable anchor c, ex- 45 tends upward. After these tiles are laid in place the spaces between the upper parts of the tiles B are entirely filled with concrete or the like, and preferably with armored con- 50 crete—i. e., concrete in which is embedded a metallic strengthening device, supporting and strengthening the concrete itself. In the form herein illustrated the device consists of tie- rods, which are indicated by d, the concrete being indicated by D. After the concrete has

set the false work below the floor can be removed and the floor is ready for use.

The advantages of this structure will be 55 readily apparent. In the first place the entire lower surface of the floor is composed of hollow tiling, which is the best possible fire- proof material and which is also practically sound-proof. The floor is also exceedingly 60 strong. The armored concrete itself being anchored by steel tie-rods possesses very great strength and can for all practical purposes be considered immovable. Each tile B bears to 65 the two adjacent concrete sections D the relation of a keystone to an arch, and consequently is firmly held in position. The tiles C of course never receive any strain and may be held by the section of the concrete or by the upwardly-projecting anchors. 70

I realize that considerable variation is possible in the details of this construction without departing from the spirit of the invention, and I therefore do not intend to limit myself to the specific form herein shown and de- 75 scribed.

I claim as new and desire to secure by Letters Patent—

1. In a device of the class described, the combination with suitable tiles, trapezoidal in cross-section and having their larger portion at the top, of a plurality of sections of armored concrete in the spaces between the tiles, and a plurality of smaller hollow tiles below 80 the concrete and having their lower faces level 85 with the bottoms of said first-named tiles.

2. In a device of the class described, the combination with suitable tiles, trapezoidal in cross-section, and having their larger portion at the top, of a plurality of sections of ar- 90 mored concrete in the spaces between the tiles, a plurality of smaller hollow tiles below the concrete extending to the bottoms of said first- named tiles, and suitable anchors securing 95 said smaller tiles to the concrete sections.

In witness whereof I have signed the above application for Letters Patent, at Chicago, in the county of Cook and State of Illinois, this 16th day of February, A. D. 1904.

DUNCAN W. BOYD.
